CLAIM

The ornamental design for a set of cabinets, as shown and described.

DESCRIPTION

FIG. 1 is a front, top, and right perspective view of a first cabinet, of a set of cabinets, showing my new design, shown separately for ease of illustration;

FIG. 2 is a rear, bottom, and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is a front, top, and right perspective view of a second cabinet, of a set of cabinets, showing my new design, shown separately for ease of illustration;

FIG. 11 is a rear, bottom, and left perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is an enlarged view of portion 18 shown in FIG. 10;

FIG. 19 is a front, top, and right perspective view of a third cabinet, of a set of cabinets, showing my new design, shown separately for ease of illustration;

FIG. 20 is a rear, bottom, and left perspective view thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a top plan view thereof;

FIG. 26 is a bottom plan view thereof; and,

FIG. 27 is an enlarged view of portion 27 shown in FIG. 19.

The claim is directed to the collective appearance of the set shown in FIGS. 1 through 27.

The dash-dash broken lines in the drawings depict portions of the set of cabinets that form no part of the claimed design. The dot-dash broken lines represent boundaries of the enlarged portions and form no part of the claimed design.

1 Claim, 27 Drawing Sheets
